Attorney

UNITED STATES PATENT OFFICE.

JOHN ALLEN JOHNSON, OF MIDDLETOWN, DELAWARE.

SUCTION ATTACHMENT FOR DENTAL PLATES.

No. 806,345.

Specification of Letters Patent.

Patented Dec. 5, 1905.

Application filed September 16, 1905. Serial No. 278,772.

To all whom it may concern:

Be it known that I, JOHN ALLEN JOHNSON, a citizen of the United States, residing at Middletown, in the county of Newcastle and

5 State of Delaware, have invented certain new and useful Improvements in Suction Attachments for Dental Plates; and I do hereby declare the following to be a full, clear, and exact description of the invention, such as will 10 enable others skilled in the art to which it appertains to make and use the same, reference being had to the accompanying drawings, and to the letters of reference marked thereon, which form a part of this specification.

15 This invention relates to new and useful improvements in suction attachments for dental plates; and the object of the invention is to produce a simple and efficient device of this character and comprises a flexible disk 20 which will act automatically in permitting the egress and preventing ingress of air and avoiding distortion or the drawing down into the chamber of the plate of the soft mucous membrane of the roof of the mouth, thus preventing 25 soreness of the mouth; and it consists, essentially, in the provision of a vulcanite plate having a recess in which an apertured metallic form is seated and having a flexible disk which is held in the form by its engagement 30 with the peripheral margin of the opening in the form, leaving the outer part of the disk free and forming a lip or valve.

With my invention the free marginal edge of the flexible rubber disk, forming a lip, presenting away from the center of the chamber, or point where partial vacuum is desired, the application of exhaust will open the valve or lip and permit the escape of the contained air in the chamber, and instantly closing upon 40 the stopping of the exhaust, being kept closed by atmospheric pressure.

My invention is illustrated in the accompanying drawings, which, with the letters of reference marked thereon, form a part of this 45 application, and in which drawings—

Figure 1 is a vertical sectional view through a vulcanite plate, showing applied thereto my suction appliance. Fig. 2 is a top plan view of the invention. Fig. 3 is a perspective view of the metallic form having an ap-

erture in its bottom to receive the flexible disk, and Fig. 4 is a perspective view of the flexible disk looking at the under surface of the same.

Reference now being had to the details of the drawings by letter, A designates a vulcanized plate of the usual construction, which is recessed at A' upon its upper surface and adapted to receive a metallic form or receptacle B, which is fastened in any suitable manner to the plate by passing pins through apertures formed in the marginal edge of the form or receptacle.

C is a disk of flexible rubber, which is inserted through a central aperture D, formed in said metallic form, and a portion of said disk which when applied to the form is in a plastic state is made to spread underneath the metal form about the central aperture therein and when the disk is hardened over 70 a flange to securely hold the disk in place. The upper portion of said disk outside the marginal line of the aperture is of a flexible nature and forms a free lip or valve to permit the escape of contained air in the chamber 75 and which will instantly close upon stopping the exhaust, it being kept closed by atmospheric pressure, thus acting automatically in permitting the egress of air and preventing the ingress of the same, and by this construction 80 the vacuum-chamber exists only in theory and by use of the appliance all distortion is prevented and the soft mucous membrane of the mouth protected against soreness.

By the provision of an appliance as shown 85 and described means is afforded whereby the disk may be easily and quickly removed in the case of any deterioration of the material and without in any way disturbing the suction of the remaining parts of the device. 90

Having thus described my invention, what I claim as new, and desire to secure by Letters Patent, is—

1. A suction appliance for dental vulcanite plates comprising, in combination with an imperforate plate having a recess in the surface thereof, a metallic form with an opening therein seated in said recess, a flexible disk having a shank portion which fills the opening in said plate and held to the latter, the 100

marginal edges of the disk being free and serving as a valve or lip adapted to seat against said plate, as set forth.

2. A suction appliance for dental vulcanite plates, comprising, in combination with a plate having a recess upon the surface thereof, a metallic form seated in said recess, a flexible disk held to said form by a portion thereof engaging the under surface of the

form about the central marginal aperture 10 therein, the outer portion of said disk forming a lip or valve, as set forth.

In testimony whereof I hereunto affix my signature in the presence of two witnesses.

JOHN ALLEN JOHNSON.
